Primary Examiner — Lilyana Bekic*Assistant Examiner* — Aula Soroush(74) *Attorney, Agent, or Firm* — Collard & Roe, P.C.(57) **CLAIM**

The ornamental design for an inhaler, as shown and described.

DESCRIPTION

FIG. 1 is a right side view of an inhaler, showing my new design;

FIG. 2 is a rear view thereof;

FIG. 3 is a left side view thereof;

FIG. 4 is a front view thereof;

FIG. 5 is a top view thereof;

FIG. 6 is a bottom view thereof;

FIG. 7 is a top, right side and rear perspective view thereof;

FIG. 8 is an enlarged detail view of line 8 in FIG. 7; and,

FIG. 9 is an enlarged detail view of line 9 in FIG. 7.

The features shown in broken lines in FIG. 6 show portions of the inhaler that form no part of the claimed design.
